PARACHUTE

Augustus John Steinthal, New York, N. Y.

Application May 22, 1951, Serial No. 227,690

6 Claims. (Cl. 244—145)

1

This invention relates to new and useful improvements in parachutes and more particularly to a parachute of the type used for dropping large and heavy objects, such as guns, tanks, and other military apparatus and supplies, or the like, from an airplane.

One of the objects of the invention is to provide a parachute having a canopy of a construction and formation formed with spaced slots extending in parallel relation and constituting passages through which air may escape, whereby the canopy will be prevented from tearing in its descent with the load attached and the control of the speed of such descent maintained.

A further object of the invention resides in the provision of a canopy formed of a plurality of spaced apart sections or segments, secured together through the medium of a plurality of transverse and longitudinal strips.

A still further object resides in the provision of a parachute in which the geometric porosity can be easily calculated, controlled, and varied as desired by changing the arrangement and dimensions of the openings.

A further object resides in the provision of a canopy with seamed edges and also with reinforcing strips extending in crossed relation to each other between marginal edges of the canopy, serving to materially reinforce the latter, certain of said strips having looped ends projecting from the margins of the canopy for engagement with shroud lines.

Still another object of the invention resides in the formation of terminal loops of double thickness to overcome possibility of tearing under strain.

A still further object resides in the arrangement of the cross strips on the canopy so that the shroud lines connected therewith will be arranged in groups and the downward pull of the load suspended from the canopy will be at the margins of the latter in such manner that pockets will be formed in said canopy, enabling the air to flow freely and effectively through the slots as the parachute descends.

A still further object resides in the provision of a parachute which is comparatively simple and durable in construction, inexpensive to manufacture and one which will be most efficient in operation.

With these and numerous other objects in view, my invention consists in the novel features of construction, combination and arrangement of parts, as will be hereinafter referred to and more particularly pointed out in the specification and claims.

2

In the accompanying drawings forming a part of this application:

Figure 1 is a plan view of the parachute, constructed in accordance with my invention;

5 Figure 2 is a fragmentary sectional view, taken through a marginal portion of the canopy, along the line 2—2 of Figure 1;

Figure 3 is a sectional view, taken along the line 3—3 of Figure 1;

10 Figure 4 is a fragmentary view upon an enlarged scale showing a marginal portion of the canopy in top plan;

Figure 5 is a sectional view, taken along the line 5—5 of Figure 4;

15 Figure 6 is a fragmentary view showing the central portion of the canopy upon an enlarged scale;

Figure 7 is a sectional view, taken along the line 1—7 of Figure 6;

20 Figure 8 is a fragmentary view upon an enlarged scale showing the looped end portion of a shroud engaging strip in top plan;

Figure 9 is a sectional view, taken along the line 9—9 of Figure 8;

25 Figure 10 is a view upon an enlarged scale, taken along the line 10—10 of Figure 11, and showing the lower portion of a shroud line and a riser carried thereby, partially in elevation and partially in section;

30 Figure 11 is a sectional view, taken along the line 11—11 of Figure 10;

Figure 12 is a view upon an enlarged scale showing a shroud line carried by a looped strip, the view being taken along the line 12—12 of

35 Figure 13;

Figure 13 is a view in elevation, looking from the left of Figure 12;

Figure 14 is a diagrammatic view illustrating the relation of the shroud lines to the canopy;

40 and

Figure 15 is a diagrammatic view showing the parachute in side elevation.

As is well known, parachutes are now being used for military and other purposes to drop large

45 and heavy articles and apparatus from airplanes. For such purposes, the canopies of the parachutes must, necessarily, be materially larger and more highly reinforced than those produced for the dropping of individuals from airplanes. By

50 the same token, the canopy must be designed differently and constructed differently, in order to give the most efficient results. The parachutes presently used for the purposes aforesaid have been found to be faulty in many respects and it

55 is the purpose of this invention to provide a parachute which will overcome the difficulties

presently encountered and which will produce the most efficient results.

To this end, I provide a parachute which consists briefly of a canopy 1, shroud or suspension lines 2 which are arranged in groups having their lower ends connected with the ends of a bar 3, and risers 4 depending from the ends of said bar 3 to which a load or, if desired, a pilot's harness may be connected.

The canopy 1 may be formed of any desired material, such as nylon, silk, plastic, or other suitable material, and is designed rectangularly, same being formed from a plurality of strips or sections 5 which extend the full width of the canopy in one direction. These strips or sections are arranged in spaced relation to form slots or spaces 6 therebetween, constituting vents through which the air may flow during the use of the parachute. These vent openings prevent tearing of the fabric or material of which the canopy is made and also serve to control, to some extent, the speed at which the descent with load attached is made.

The side edge portions of the strips or sections 5 are folded inwardly upon themselves to form flat hems 7, as shown in Figure 2 of the drawings, and in referring to this figure, it will be seen that the fabric or other material in the form of reinforcing tapes or narrow strips 8 extend along upper surfaces of the hemmed edges, same being secured by lines of stitching 9 which also serve to secure the seams. Opposite ends of the strips or sections 5 are folded to form flat hems 10, secured by lines of stitching 11.

The end sections of the canopy are designated by the numeral 5' and it will be seen that while the inner side edges of these end sections are formed with hems corresponding to the hems 7, as shown in Figure 3, the outer side edge portions thereof are folded to form hems 12 which are secured by lines of stitching 13 and reinforced by tapes or strips 14 enclosed within the hems, as best shown in Figure 5 of the drawings.

Extending transversely of the canopy in crossing relation to the sections 5 and 5' are the strips or tapes 15 and 16, arranged in spaced and alternating relation to each other, same being secured flat against said sections by rows of stitching 17 and 18. Additional strips 19 are provided, same being secured against the under faces of the sections 5 in alignment with the strips 15 and 16, as best shown in Figure 2. These strips 16 have their end portions folded downwardly and inwardly to form turned under ends 20 which are firmly secured against the reinforcing strips 21 extending longitudinally of the outer side edge portions of the end sections 5', as shown in Figure 5 of the drawings.

The strips or webs 15 and 19 are of such length that the end portions thereof extend beyond the outer side edges of the end sections 5' and are folded back upon themselves, as shown at 15' and 19', to form extensions 22 which are stitched together by lines of cross-stitching 23 and forming loops 24 of double thickness, as best shown in Figure 9 of the drawings.

Strips 25, corresponding to the strips 15 and 19, extend longitudinally of alternate sections 5 and have extended end portions folded and secured to form loops 26, corresponding to the loops 24. It will thus be seen that the canopy which has the outline of a rectangle when flattened out, as shown in Figure 1, and also in Figure 14, has a multiplicity of loops arranged in spaced relation to one another longitudinally of the side edges of

said canopy, in addition to the spaced loops at the end edges thereof.

At the center of the canopy, as best shown in Figure 6 of the drawings, are strips 27 which are secured by lines of cross-stitching 28 which have crimped or overlapped central portions forming loops 29, to which a static line may be secured. These loops 29 may be formed from separate strips, as shown, or same may be formed from central portions of the strips 15 and 25 which cross at the center of the canopy.

The shroud lines 2 are each formed from companion strips 30 which may be made of canvas or other suitable material and stitched together in face-to-face engagement. Eyes 31 having shanks 32, mounted longitudinally between upper portions of the strips 30 project from the upper ends of the shroud lines and are adapted for engagement with the loops 24 and 26 projecting from the canopy. The outer or lower portions of the shroud lines are reinforced by strong cords or rods 33 and the outer ends of said shroud lines are provided with eyes 34 which are engaged with the ring members 35 to which the ends of the risers 4 and the spreader bar 3 are connected, as best shown in Figures 10 and 11 of the drawings.

Referring particularly to Figures 14 and 15 of the drawings, it will be seen that there are twenty shroud lines, ten of which are connected with one of the rings 35 and the remainder connected with a similar ring. While I do not wish to be limited necessarily to any particular number of shroud lines, it will be seen that said lines are arranged in two groups, so that the pull will be evenly distributed along the marginal edges of the canopy as the parachute descends. When and if this construction of parachute is used by an individual, it will enable him to pull the shroud lines to tilt the canopy on one side or the other and thus assist in guiding the descent.

From the foregoing description of the construction of my improved parachute, the method of assembling same and the use thereof will be readily understood, and it will be seen that I have provided a comparatively simple, inexpensive and efficient means for carrying out the various objects of the invention.

While I have particularly described the elements best adapted to perform the functions set forth, it is apparent that various changes in form, proportion and in the minor details of construction may be resorted to, without departing from the spirit or sacrificing any of the principles of the invention.

Having thus described my invention, what I claim is:

1. A parachute comprising a rectangular canopy having sections spaced transversely from each other and providing air outlets spaced between the said sections, strips secured across said sections, strips secured longitudinally upon certain of said sections, the last mentioned strips and alternate ones of the first strips having end portions extending from edges of the canopy and folded back upon themselves and secured to form loops spaced from each other longitudinally of margins of the canopy and connected therewith by shanks of multiple thickness, a cross bar, rings to which opposite ends of the cross bar are connected, shroud lines having upper ends individually connected with companion ones of said loops, said shroud lines being arranged in groups and having lower ends of the shroud lines of the groups being connected with the rings at

opposite ends of the cross bar, and risers connected with and extending downwardly from said rings.

2. A parachute comprising a canopy of rectangular outline and having elongated air escape openings extending in one direction the full distance between opposite sides edges of the canopy, strips secured against the canopy and extending across the same in crossed relation to each other and formed at their ends with loops projecting from marginal edges of the canopy and spaced from each other longitudinally of the side edges, certain of said strips extending across the outlet openings and serving to limit spreading of the openings, shroud lines having upper ends connected with said loops, lower ends of selected ones of said shrouds being brought together and connected with rings and thereby forming groups of shrouds, and a cross bar extending between and having its ends connected with the rings.

3. A parachute comprising a canopy of rectangular outline consisting of a plurality of sections spaced transversely from each other and thereby providing air escape openings in the canopy, strips extending across the canopy transversely of said sections and secured thereto, other strips extending across the canopy longitudinally of certain of the sections and secured thereto, certain of said strips having end portions projecting from marginal edges of the canopy and folded back upon themselves and secured in lapped relation to the sections and forming loops having shanks of multiple thickness, shrouds having eyes at upper ends engaged through said loops, there being eyes at lower ends of the shrouds and providing groups of shrouds connected at their lower ends, and a cross bar extending between and at its ends connected with said rings.

4. A parachute comprising a canopy of rectangular outline consisting of a plurality of sections spaced transversely from each other and thereby providing air escape openings in the canopy, strips extending across the canopy transversely of said sections and secured thereto, other strips extending across the canopy longitudinally of certain of the sections and secured thereto,

certain of said strips having end portions formed with loops projecting from margins of the canopy, and shrouds having eyes at their upper ends engaged through said loops and suspending the shrouds from the loops.

5. A parachute comprising a canopy of rectangular outline consisting of a plurality of sections extending the full width of the canopy in one direction between opposite side edges thereof and disposed in transversely spaced relation to each other and forming air escape slots between the said sections for the full length thereof, and shroud lines connected with said sections and spaced from each other longitudinally of marginal edges of the canopy and extending downwardly therefrom.

6. A parachute including a canopy of rectangular outline having elongated sections extending the full distance between opposite side edges and having straight side edges spaced transversely from each other and thereby forming air escape slots between spaced edges of the said sections for the full length thereof and each of the same width throughout its length, strips mounted against upper surfaces of said sections and extending the full distance between opposite side edges of the canopy, certain of said strips extending across the slots and limiting spreading of the slots, and shroud lines connected with ends of the strips and extending downwardly from the canopy.

AUGUSTUS JOHN STEINTHAL.
